UNITED STATES PATENT OFFICE.

HARRY HOMES HODGSON, OF NEW ORLEANS, LOUISIANA.

TYPE-WRITING MACHINE FOR THE BLIND.

SPECIFICATION forming part of Letters Patent No. 727,141, dated May 5, 1903.

Application filed November 14, 1902. Serial No. 131,413. (No model.)

To all whom it may concern:

Be it known that I, HARRY HOMES HODGSON, a citizen of the United States, residing at New Orleans, in the parish of Orleans and State of Louisiana, have invented certain new and useful Improvements in Type-Writing Machines for the Blind; and I do declare the following to be a full, clear, and exact description of the invention, such as will enable others skilled in the art to which it appertains to make and use the same, reference being had to the accompanying drawings, and to the figures of reference marked thereon, which form a part of this specification.

The object of my invention is to provide a new and improved form of type for writing-machines that the writing of such machines may be read by the blind.

In the drawings, Figure 1 shows in section a common form of writing-machine with my type attached thereto. Fig. 2 is a view of the printing-face of my type. Fig. 2^a is a view of the printing-face of the ordinary printing-type. Figs. 3 and 4 are views in cross-section on the line 3 3 of Fig. 2.

The object of my invention is to provide a type which will indent the paper sufficiently to form embossed or raised letters which may be read by the blind by passing the tips of their fingers over the same. The letters are formed in relief on the side of the paper opposite the side which receives the impress of the type. My types differ from the ordinary printing-type in the fact that they are positive-faced.

Fig. 2 shows the face of my type, and it will be seen that such type presents the letters positive-faced as such letters are seen in ordinary printed matter. In Fig. 2^a the ordinary form of printing-type is shown, in which the letters as seen from the face of the type are negative-faced. I therefore employ the words "positive-faced" to designate type cast with the letters to appear from the face of the type as such letters appear in the ordinary print.

In order that the type may the more easily emboss the paper and form letters with clear outlines, it is requisite that the edge of the type formed by the face and sides should be sharp and distinct and so formed as not to wear dull or rounded. To such end I prefer-

ably form the type as shown in Fig. 3. In such figure the character 10 indicates the base-plate of the type extended into a shank, 55 by which it is attached to the type bars or levers, and the character 11 indicates the type proper. As shown, the sides of the type converge or slant inwardly from the base-plate to the face, and the face is slightly concaved 60 there by giving an acute angle to the edge of the type, while the converging sides give support to such edge to prevent it being flattened outwardly. By reason of this construction when the type is forced down on the paper the sharp angle of the edge causes the fibers of the paper to be more sharply bent and forms an embossed or raised letter on the opposite side of the paper with clear and well-defined outlines. It will also be noted that 70 by reason of such sharp outline the type enters the paper the more readily and the letters are embossed with less force than would be otherwise required. Thus I am enabled to use my type in the ordinary form of type-writing machine in which the type-carrying levers are pivoted and are operated by horizontal key-carrying levers, as shown in Fig. 1. In such form of machine the ordinary positive-faced embossing-type cannot be 80 used, as the key-carrying lever cannot ordinarily be struck with sufficient force to cause the type to form a letter which may be read only by the sense of touch. Also by reason of the sharper outline given to the embossed 85 letter the character is more easily and certainly determined by the tactile sense, and a smaller character may be used than has heretofore been possible.

While I prefer the form of type above described, I may also employ a type having parallel sides and a concave face, as shown in Fig. 4.

By preference I use a type of the Gothic form, as shown—that is, a type without 95 serifs. Such a type I mount on the ends of the type bars or levers in any well-known manner. The type-bars are pivoted to the frame of the machine and are operated by horizontal key-carrying levers. The paper is 100 carried around the well-known form of roller-platen, and such platen should be formed with a soft surface and should be arranged to feed or move in the direction opposite to

that in which it is moved when the ordinary form of printing-type is employed.

The type may be made slightly larger than the ordinary printing-type, in which case the 5 roller should also be correspondingly enlarged.

Having thus described my invention, I claim—

1. The combination in a writing-machine 10 with a roller-platen, pivoted type-carrying levers, and means for operating same, of positive-faced type having concaved faces and converging sides carried by such levers and arranged to form raised characters, substantially as described.

2. The combination in a writing-machine 15

with a platen, type-carrying means, and operating means therefor, of positive-faced type, having concaved faces, substantially as described.

3. The combination in a writing-machine 20 with a platen, and type carrying and operating means, of positive-faced type having converging sides and concave faces, substantially as described.

In testimony whereof I affix my signature 25 in presence of two witnesses.

HARRY HOMES HODGSON.
